WASHING MACHINE

John Bochan, Louisville, Ky., assignor to General Electric Company, a corporation of New York
Filed Apr. 12, 1966, Ser. No. 542,100
3 Claims. (Cl. 68—208)

This invention relates to clothes washing machines and, more particularly, to an improved pump drive arrangement for use in such machines.

Many clothes washing machines marketed today are operable at a plurality of pre-selectable speeds. This capability is advantageous because it enables the user to tailor the wash agitation and spin speeds to the types of fabrics being washed as well as to the size of the load. Many of these machines utilize a multi-speed motor to provide their selectively variable speed of operation. Such machines are desirable because of their speed selectivity; however, they have a serious shortcoming. The motor is usually effectively coupled directly to the pump. This causes the pump to operate at a speed proportional to the motor speed. If the pump is optimized for the higher motor speed, its effective head at low motor speeds will be only marginal at best. If the pump is optimized for the lower motor speed, its velocity will be too large at high motor speeds. This causes excessive sudsing, particularly during recirculation. Also, the pump out volume is more than some standpipes can handle.

It is an object of this invention to provide an improved multi-speed washing machine which provides optimum pump operation.

It is another object to provide such a machine in which the pump is operated at a constant speed.

It is a further object to provide a washing machine having a multi-speed drive motor connected to a pump through a mechanism including a governor clutch.

In carrying out my invention, in one form thereof, I provide a fabric washing machine having a receptacle to receive fluid and fabrics to be washed in the fluid and agitation means to cause a washing action on the fabrics. I also include a multi-speed motor, connected to the agitation means so as to drive it at a selected one of a plurality of speeds. A pump is included to drain fluid from the receptacle, and may recirculate fluid as well for filtering purposes. The motor is drivingly connected to the pump by means including a governor clutch adapted to drive the pump at a predetermined speed regardless of the speed of the motor.

The subject matter which I regard as my invention is particularly pointed out and distinctly claimed in the concluding portion of the specification. My invention, however, both as to organization and method of operation, together with further objects and advantages thereof may best be understood by reference to the following description taken in conjunction with the accompanying drawing.

In the drawing:

FIGURE 1 is a schematic front elevational view of a clothes washing machine incorporating my invention, the view being partly broken away and partly in section to illustrate details, and

FIGURE 2 is an elevational view of a governor clutch suitable for use in the machine of FIGURE 1, the view being partly in section to illustrate details.

Referring now to FIGURE 1, I have shown therein an agitator type clothes washing machine 1 having a conventional basket or clothes receiving receptacle 2, provided over its side and bottom walls with perforations 3 and disposed within an outer imperforate tub or casing 4. The basket and tub together form a receptacle to receive fluid and fabrics to be washed in the fluid. The basket

2

may be provided with a suitable balance ring 5 to help steady the basket when it is rotated at high speed.

Tub 4 is rigidly mounted within an appearance cabinet 7, which includes a cover 8 hingedly mounted in a top portion 9 of the cabinet to provide access through an opening 10 to the basket. The rigid mounting of tub 4 within cabinet 7 may be effected by any suitable means, for instance, strap members could be provided, each of which is secured at one end to the cabinet and at the other end to the outside of the tub. At the center of basket 2 there is positioned a vertical axis agitator 11 which includes a center post 12 in a plurality of curved water circulating vanes 13 joined at their lower ends by an outwardly flared skirt 14.

Both the clothes basket 2 and the agitator 11 are rotatably mounted. The basket is mounted on a flange 15 of a hub 16 and the agitator 11 is mounted on a shaft 17 which extends upwardly through the hub 16 and through the center post 12 and is secured to the agitator so as to drive it. During a cycle of operation of the machine 1, liquid is introduced into the tub 4 and basket 2, and the agitator 11 is then oscillated back and forth on its axis, that is, in a horizontal plane within the basket, to wash the clothes therein. Then, after a predetermined period of this washing action, basket 2 is rotated at high speed to extract centrifugally the washing liquid from the fabrics and discharge it to drain. Following this extraction operation, a supply of clean liquid is introduced into the basket for rinsing the clothes and the agitator is again oscillated. Finally, the basket is once more rotated at high speed to extract the rinse liquid.

The basket 2 and agitator 11 may be driven through any suitable means from a multi-speed, power source. By way of example, I have shown them as driven from a multi-speed motor 18 through a drive including a clutch 19 mounted on the motor shaft. The motor is tailored so as to be used to its full extent when it accelerates the basket 2 up to spin speed, and in order to assist the motor during its starting, clutch 19 allows the motor to start without a load and then accept the load as it comes up to speed. A suitable belt 20 transmits power from clutch 19 to a transmission assembly 21 through a pulley 22. Thus, depending on the direction of motor rotation, pulley 22 of transmission 21 is driven in opposite directions. The transmission 21 is so arranged that it supports and drives both the agitator drive shaft 17 and the basket mounting hub 16. When the motor 18 is rotated in one direction, the transmission causes agitator 11 to oscillate in a substantially horizontal plane within the basket 2. Conversely, when motor 18 is driven in the opposite direction the transmission rotates the clothes basket 2 and agitator 11 together at high speed for centrifugal liquid extraction. While the specific type of transmission used does not form part of the invention, reference is made to Patent 2,844,225 issued to James R. Hubbard et al. on July 22, 1958 and owned by the General Electric Company, assignee of the present invention. That patent discloses in detail the structural characteristics of a transmission assembly suitable for use in the illustrated machine.

In addition to operating the transmission 21, as described, motor 18 also provides the driving force for a pump structure generally indicated at 23. The motor to pump connection is provided by the motor shaft 24, a governor clutch 25, a flexible coupling 26 and a pump shaft 27. The pump 23 may include two separate pumping units 28 and 29 both operated simultaneously in the same direction by motor 18. Pump unit 28 has an inlet which is connected by a conduit 30 to opening 31 formed at the lowermost point of tub 4. Pump unit 28 also has an outlet which is connected by a conduit 32 to a suitable drain (not shown). Pump unit 29 has an inlet connected

by a conduit 33 to the interior of tub 4 and an outlet connected by a conduit 34 to a nozzle 35. Nozzle 35 is positioned to discharge into a filter pan 36 secured on the top of agitator 11 so as to be movable therewith. Both pumps are formed so that in the spin direction of rotation pump unit 28 will draw liquid from opening 31 through conduit 30 and discharge it through conduit 32 to drain, and, in the other direction of rotation, pump unit 29 will draw in liquid through conduit 33 and discharge it through conduit 34 and nozzle 35, each of the pumps being substantially inoperative in the direction of rotation in which it is not used. With this structure, then, when the motor is rotating so as to provide agitation, pump unit 29 draws liquid through conduit 33 and discharges it through conduit 34 so that the liquid passes from nozzle 35 into filter pan 36, and then down through a number of small openings provided in the bottom of the filter pan back into the basket 2. In this manner, the filter pan 39, with its small openings 41 in its upstanding side wall 42, causes lint which is separated from the clothes during the washing operation to be filtered out of the water and thus prevents it from being re-deposited on the clothes.

The motor 18, transmission 21, basket 2, agitator 11 and their associated element 2 form a suspended washing and centrifuging system which is supported by the stationary structure of the machine (which includes tub 4) so as to permit isolation of vibrations from the stationary structure. While any suitable suspension structure may be used, I prefer to use a suspension structure which includes a bracket member 37 with transmission 21 mounted on the top thereof and motor 18 mounted to the underside thereof. The bracket member in turn is secured by upwardly extending rigid members 38, and each of the two upwardly extending members 38 is connected to a cable 39 supported from the top of the machine. While only a portion of the suspension system is shown in the drawing, such a vibration isolation system is fully described and claimed in my prior Patent No. 2,987,190, issued on June 6, 1961, and assigned to the General Electric Company, assignee of the present invention. Such a suspension system provides for flexible support of the moving system so as to isolate the vibrations in that system from the casing and machine.

In order to accommodate the movement which occurs between basket 2 and tub 4 without any danger of leakage between them, the stationary tub 4 is joined to the upper part of transmission 21 by a suitable flexible boot member 40. A suitable and highly effective structure of this type is described and claimed in my prior Patent No. 2,959,966, issued on Nov. 15, 1960, and assigned to the General Electric Company, assignee of the present invention.

Hot and cold water may be supplied to the machine through conduits 41 and 42 which are adapted to be connected respectively to sources of hot and cold water (not shown). Conduits 41 and 42 extend into a conventional mixing valve structure 43 having solenoids 44 and 45 so that energization of solenoid 44 permits passage of hot water through the valve to a hose 46, energization of solenoid 45 permits passage of cold water through the valve, and energization of both solenoids permits mixing of hot and cold water in the valve and passage of warm water into hose 46. Hose 46 is positioned to communicate with a nozzle 47 positioned to discharge into basket 2 so that when one or both of the solenoids 44 and 45 is energized, water enters into the basket 2 and tub 4. The level to which the water rises in the basket 2 and tub 4 may be controlled by any suitable water level control means, many of which are well known in the art.

A control circuit normally is included to control the operations of the various components of the machine and would include appropriate parts so that the user may control the speed of multispeed motor 18 so as to select a wash and rinse agitation speed and extraction spin speed

by utilizing controls such as rotatable member 48 and switches 49. The particular control circuit does not form a part of my invention and a number of such circuits are well known in the art. Therefore, for the sake of simplicity, a particular circuit has not been illustrated.

As an important aspect of my invention, I cause the multispeed motor to drive the pump 23 as substantially a constant speed, regardless of the speed of the motor. For this purpose governor clutch 25 is included between the motor shaft 24 and the pump 23. Referring now particularly to FIGURE 2 it will be seen that the governor clutch 25 includes a drum 50 mounted on motor shaft 24 for rotation therewith and a carrier member 51 formed as an extension of pump shaft 27. The carrier member 51 may be supported on motor shaft 24 by a ball bearing mechanism 52 so as to be freely rotatable with respect to the motor shaft. The carrier member 51 includes a flange 54 which is parallel to and radially spaced from the outer surface of drum 50. A number of clutch shoes, for instance two as illustrated at 55 are mounted on the flange by means of stems 56 which extend through cooperative openings 57 in the flange 54. Thus the carrier member 51 and the clutch shoes 55 are effectively interconnected so that they will rotate together while, at the same time, the clutch shoes 55 are free to move radially outwardly away from the drum 50. The shoes are normally biased against the drum 50 by springs 58, which are mounted between the shoes 55 and the flange 54. Each of the shoes additionally includes a coating or layer of friction material 59 formed on its radially inward surface so that, as long as the coating 59 is in engagement with the drum 50, torque will be transmitted to the carrier member and thereby to the pump so as to rotate the pump. When the speed of the carrier member has reached a predetermined value the mass of the shoes will be sufficient to react in response to centrifugal force and compress the associated spring 58. This will reduce the force between friction coatings 59 and drum 50 sufficiently that the shoes will slip with respect to the drum. Thus the pump 23 will always be rotated at a constant speed regardless of the speed of the motor 18 and the pumping units 28 and 29 may be optimized so as to give complete satisfactory performance. For best results the governor clutch 25 should be constructed so that the slip speed, that is the speed at which the shoes will slip with respect to the drum, is below the lowest motor speed.

The foregoing is a description of an illustrative embodiment of the invention, and it is my intention in the appended claims to cover all forms which fall within the scope of the invention.

What I claim as new and desire to secure by Letters Patent of the United States is:

1. A fabric washing machine including a receptacle to receive fluid and fabrics to be washed in the fluid; agitation means adapted to cause a washing action on the fabrics; multi-speed drive means connected to said agitation means to drive said agitation means at a selected one of a plurality of speeds; a pump adapted to remove fluid from said receptacle; connection means drivingly connecting said drive means to said pump; said connection means including a governor clutch adapted to drive said pump at a predetermined speed regardless of the speed of said drive means.

2. A fabric washing machine including a receptacle to receive fluid and fabrics to be washed in the fluid; agitation means adapted to cause a washing action on the fabrics; a multi-speed motor connected to said agitation means to drive said agitation means at a selected one of a plurality of speeds; a pump adapted to remove fluid from said receptacle; connection means drivingly connecting said drive means to said pump; said connection means including a governor clutch adapted to drive said pump at a predetermined speed regardless of the speed of said drive means.

3. A fabric washing machine including a receptacle to receive fluid and fabrics to be washed in the fluid; agitation means adapted to cause a washing action on the fabrics; a multi-speed motor connected to said agitation means to drive said agitation means at a selected one of a plurality of speeds; a pump adapted to remove fluid from said receptacle; said motor having an output shaft; a drum mounted on said shaft for rotation therewith; a drive shaft connected to said pump; a carrier member connected to said drive shaft and extending in spaced relationship with the outer surface of said drum; a plurality of clutch shoes drivingly mounted on said carrier member with freedom of radial movement; and spring

means yielding each of said clutch shoes into engagement with said drum; said shoes being adapted to move radially outward to disengage said pump from said motor in response to a predetermined speed of said motor.
